UNITED STATES PATENT OFFICE.

JOHN WHITE, OF EDINBURGH, SCOTLAND.

PULP-BEATING ENGINE.

SPECIFICATION forming part of Letters Patent No. 784,822, dated March 14, 1905.

Application filed January 9, 1905. Serial No. 240,146.

To all whom it may concern:

Be it known that I, JOHN WHITE, a subject of the King of the United Kingdom of Great Britain and Ireland, residing at Edinburgh, 5 Scotland, have invented a certain new and useful Improvement in Pulp-Beating Engines, of which the following is a specification.

This invention relates to pulp-beating engines or "Hollanders" of the kind referred to in United States Patent No. 757,585, of April 19, 1904, wherein the knife-plate is trained or adjusted to the beating-roll; and the present improvement has for its object to simplify the construction and operation of the 15 movable knife-plate and plate-box and adapt the latter to be applied to existing beaters without involving structural alterations thereof, while it may also be applied to beaters of modern designs.

20 In the accompanying drawings, which illustrate the invention, Figure 1 is a longitudinal section of part of the trough of a pulp-beating engine or "Hollander," showing in cross-section the knife-plate box and relative parts 25 and indicating part of the knife-roll. Fig. 2 is a section at right angles to Fig. 1 of the knife-plate box. Fig. 3 is a sectional view corresponding to Fig. 1, but showing a modified construction.

30 As shown by Figs. 1 and 2 of the drawings, the plate-box A is made externally to fit into the usual opening or den B in the trough C, and internally it assumes the form of a rectangular fluid-pressure chamber A', in which 35 is fitted a rectangular piston or ram D, carrying within it a series of blades or knives D', protruding above its upper surface and forming the usual knife-plate. The piston or ram D is acted on by fluid under pressure admitted 40 to the chamber A' through an inlet α and regulated so as to raise the knife-plate into more or less close contact with the knives of the beating-roll E. Suitable packing F, held by an accurately-fitted gland G, prevents escape of 45 fluid from the chamber A' past the sides of the ram D. The pressure may be regulated by employing a head of water, which may be va-

ried as desired, so as to maintain the knife-plate in proper position relatively to the beating-roll E, which is maintained in a fixed position after being set in the usual way. By this arrangement the knife is practically floated and caused by the fluid-pressure to follow any slight movement or oscillation of the beater-roll.

50 In the modification represented at Fig. 3, the water instead of being admitted directly into the pressure-chamber A' is delivered into a flexible bag H, which is thereby expanded to press on the piston or ram D, the water-pressure to such extent acting indirectly to operate the said ram.

55 In the modification represented at Fig. 3, the water instead of being admitted directly into the pressure-chamber A' is delivered into a flexible bag H, which is thereby expanded to press on the piston or ram D, the water-pressure to such extent acting indirectly to operate the said ram.

60 The movement of the knife-plate in each case may be limited by suitable stops, such as the pins I on the plate-box A entering into slots J in the ram D.

65 Having now described my invention, what I claim, and desire to secure by Letters Patent of the United States, is—

1. In a pulp-beating engine the combination 70 of a plate-box adapted to fit externally the usual opening in the beater-trough and forming internally a fluid-pressure chamber, a movable ram or piston closely fitted into said chamber, carrying knives to constitute a knife-75 plate and adjustably supported by fluid-pressure in said chamber.

2. In a pulp-beating engine the combination 80 with the beater-trough and its roll of a plate-box comprising a fluid-pressure vessel, a ram or piston fitted therein and a knife-plate supported in contact with the beater-roll by said ram or piston.

3. In a pulp-beating engine, the combination 85 with the beater-trough and its roll, of a plate-box comprising a ram casing or chamber, a ram or piston fitted therein and a knife-plate supported in contact with the beater-roll by said ram or piston, and a flexible water-pressure bag interposed in said casing between 90 the bottom thereof and the ram or piston.

4. In a pulp-beating engine, the combination 95 with the beater-trough and its roll, of a plate-box adapted to fit the opening in the beater-

trough and forming internally a fluid-pressure chamber, a movable ram or piston closely fitting said chamber and carrying knives to constitute a knife-plate, means for raising 5 the ram by the action of fluid under pressure and stops for limiting the movement of said ram.

In testimony whereof I have signed my name to this specification in the presence of two subscribing witnesses.

JOHN WHITE.
